UNITED STATES PATENT OFFICE.

GEORGE HARDY CLARK, OF WATERLOO, IOWA.

GAME APPARATUS.

1,131,210.

Specification of Letters Patent.

Patented Mar. 9, 1915.

Application filed May 23, 1914. Serial No. 840,537.

To all whom it may concern:

Be it known that I, GEORGE HARDY CLARK, a citizen of the United States of America, and a resident of Waterloo, Blackhawk 5 county, Iowa, have invented certain new and useful Improvements in Game Apparatus, of which the following is a specification.

My invention relates to improvements in games, and particularly to that type of 10 games in which a missile or throw-stick or other projectile is cast into or against different objects from spaced bases, with the purpose of successfully achieving a complete round of the goals with a minimum of casts 15 or strokes of the missile.

The object of my improvement is to furnish a new and desirable arrangement in the arrangement and form of the objects or 20 goals as acted upon by an improved form of missile or throw-stick. This object I have accomplished by the means which are hereinafter described and claimed, and which are illustrated in the accompanying drawings, in which:

25 Figure 1 is a perspective view of a receptacle having sides of differing heights, and used as one of the goals. Fig. 2 is a front elevation of a wicket having relatively narrowly spaced uprights. Fig. 3 is a front elevation 30 of another wicket, in which the uprights are more broadly spaced apart. Fig. 4 is a front elevation of a standard and removable pennant thereon. Fig. 5 is an elevation of one of the base stakes. Fig. 6 is a 35 longitudinal central section of one of the missiles or throw-sticks. Fig. 7 is an elevation of one of the longer bowler pins. Fig. 8 is an elevation of a shorter bowler pin. Fig. 9 is a perspective view of one of 40 the base-blocks for the longer bowler pins, while Fig. 10 is a similar view of a base-block for the shorter bowler pin, and Fig. 11 is a like view of one of the triangular or 45 wedge-like bases. Fig. 12 is the game diagram.

Similar characters of reference denote corresponding parts throughout the several views.

Referring first to Figs. 1 to 11 inclusive, 50 H in Fig. 1 denotes a goal receptacle which comprises four uprights h^4 , of like form and size, spaced apart, but connected together by the following means: The characters h , h^1 , h^2 , h^3 , and h^8 denote respectively the four 55 sides and the bottom of a rectangular casing made of canvas or other flexible but firm ma-

terial, and the upper edges of the canvas being secured in tubular form to receive the four cross-bars h^5 . The ends of the said bars are inserted removably in sockets formed in said uprights at appropriate heights, the uprights being seated within the upright angles of the casing to extend downwardly through holes in the casing with their lower extremities pointed to be readily fixed in the ground. The character h^6 denotes similar cross-bars which have their ends placed in like sockets in said uprights but spaced below the bottom of said casing, while tie-strings h^7 are secured from the bottom of the sides of the casing and passed about the cross-bars h^6 . By this means, the sides of said casing are stretched and made taut. The two adjacent sides h and h^1 are of the same vertical height, but the side h^2 is of greater vertical width, the bar h^5 supporting the same being secured to the uprights h^4 above the level of said sides h and h^1 . The side h^3 is still wider vertically than the side h^2 so as to be spaced above the latter. The above arrangement of the three sides h^1 , h^2 and h^3 , places them at successively greater elevations, for a purpose to be hereinafter described. The wicket I has narrowly spaced vertical uprights i 80 connected by spaced horizontal bars i^1 , i^2 , with the lower ends of the uprights sharpened to be driven into the ground. This wicket will be hereinafter referred to by name of "middie." Fig. 3 shows a wicket J comprising uprights j connected by spaced horizontal bars j^1 , j^2 , the spacing between the uprights being wider than with said middie, and the uprights themselves shorter, with the latter similarly pointed for easy 85 insertion into the soil. The pointed base-stake A as also the wedge-shaped block C, are used as will be hereinafter described to indicate the bases or locations from which the player casts the throw-stick B toward 90 the various goals. The stick B is of a cylindrical form, centrally longitudinally oriented, with short cylindrical weights of metal plugged into the ends of the orifice to lend to the missile the necessary weight. The 95 pins F and G, hereinafter called bowlers, are of cylindrical shape, the bowler G being shorter. The single shorter bowler G is to be placed on a base-block D of wedge-shape, while the bowlers F are placed in pair on 100 the base-block E also of wedge-shape, on the outer limits of the transverse grooves 110

on the top thereof, in spaced relation. The character K denotes the ensign of each player, which consists of the assemblage of a stick k having an offset top part k², with 5 a metallic or rigid pennant k¹ removably seated on said part k², the lower end of the stick being pointed for insertion into the ground.

The above described parts are all those 10 which are employed in my improved game apparatus, but one of each being used, except that each player is supplied with three throw-sticks B, each set of sticks being painted with an individual color, while a 15 pair of bowlers F are used on one base-block E, and seven of each of the base-blocks C and base-stakes A are used to indicate the locations of the seven bases in the game. Each player is also supplied with 20 one stick and pennant K, having an individual color to correspond with the color of his throw-stick.

Referring now to the diagram of the locations of the bases and goals shown in Fig. 25 12, the bases are all equally spaced from the goals, and are so arranged that in casting, there is no interference between the sections 1 to 7, it being understood that seven sections constitute one round of the game. In 30 each section are placed one each of the base-stakes A and base-blocks C, the players usually being stationed at the stakes A, but the blocks C are alined on the sections at a less distance from the goals, and are to be 35 used only by children or others not able to cast as far as the experienced or stronger players. As preferably laid out, each stake A should be twenty-one feet from the center of the goal in the same section, while the 40 block should be located but seventeen feet from the same goal. The following is the preferred sequence of goals in the different sections 1 to 7 inclusive: section 1, the wicket J; section 2, the lowest side h¹ of the receptacle H; section 3, the side h² of intermediate height of said receptacle; section 4, the middle I; section 5, the single bowler G; section 6, the highest side h³ of the receptacle H; and section 7, the pair of bowlers F 45 on their base-block E. The players may plant their flag-sticks K on any part of the play-ground, at such times as their relative scores in the game authorize the placing of either the flag-stick alone or with the pennant added.

Method of playing the game.—While the sections are preferably arranged relatively as shown in the diagram Fig. 12, yet they may be arranged differently, and the different sections may be placed relatively to each other as convenient. A game comprises the counts of all casts, whether successful or unsuccessful made in five rounds of the sections, the object being to make the goals in 60 a minimum number of casts, the bogey be-

ing a single cast for each goal, or thirty-five in five rounds of the goals. Under a certain limit or number of casts of the throw-sticks, each player is entitled to plant his flag-stick with the pennant thereon, while under a certain higher limit, he may plant only the stick without the pennant, but above the last limit he is not entitled to plant the stick on the ground. In the section 1, the player must cast his throw-stick through the 75 wicket, and each cast is counted against him. In section 2 the stick must be cast over the side h¹ into the receptacle, as is also the case in sections 3 and 6. In section 4, the stick must be cast through the middle I. In sections 5 and 7, the stick must be cast to knock down the single bowler G or the pair of bowlers F at a single cast each.

The game may be played by either one, 80 two, three or four players.

The receptacle H is so constructed as to be readily disassembled, the cross-bars h⁵ being slipped from their sockets by stretching the flexible canvas of the sides or casing.

The game is easily learned and affords 90 scope for much skill and practice.

Having described my invention, what I claim as new, and desire to secure by Letters Patent, is:

1. An inclosure, comprising a plurality of 95 spaced stakes, and a flexible cover stretched about said stakes to provide three sides of respectively increasing altitudes, the cover being closed at the bottom between the stakes.

2. A receptacle with sides of differing elevations, and an elongated throw-stick therefor, said stick having weights plugged into its ends.

3. A receptacle having four sides, of 105 which two are of the same height, while the other sides are offset in different heights from the sides of even height, the upper edges of the said sides being horizontal.

4. A receptacle of rectangular form, having three of its sides offset to be of differing heights, and an elongated throw-stick of less length than either side to be cast thereinto.

5. A combination game, comprising a receptacle with sides of differing heights, an elongated throw-stick adapted to be cast thereinto from a base, separately stationed wickets through which the throw-stick may be cast from a base, and pins which may be 115 toppled over by said throw-stick when cast from bases spaced therefrom.

6. A game, comprising a throw-stick, base-stakes, a like number of goals located at equal distances from the bases, one goal being a wicket; a second goal being a receptacle having its sides of differing heights of which the lowest is cleared in making this goal; a third goal being the same receptacle in which the side of intermediate height is 125 130

cleared in making the goal; a fourth goal being a wicket of narrower aperture than the first-mentioned wicket; a fifth goal being a single bowler pin; a sixth goal being 5 the above-mentioned receptacle in which the highest side is cleared in making this goal, and a seventh goal comprising a pair of spaced bowler-pins.

7. A game, comprising a throw-stick, base-10 stakes, a like number of goals located at equal distances from the bases, one goal being a wicket; a second goal being a receptacle having its sides of differing heights of which the lowest is cleared in making this 15 goal; a third goal being the same receptacle in which the side of intermediate height is

cleared in making the goal; a fourth goal being a wicket of narrower aperture than the first-mentioned wicket; a fifth goal being a single bowler pin; a sixth goal being 20 the above-mentioned receptacle in which the highest side is cleared in making this goal, and a seventh goal comprising a pair of spaced bowler-pins, and a flag-stick and removable rigid pennant therefor for the use 25 of each player.

Signed at Waterloo, Iowa, this 7th day of May, 1914.

GEORGE HARDY CLARK.
